JOSEPH D. DENBURGER, OF LENTS, OREGON.

MACHINE FOR CALKING SEAMS.

1,277,049.

Specification of Letters Patent. Patented Aug. 27, 1918.

Application filed December 10, 1917. Serial No. 206,525.

To all whom it may concern:

Be it known that I, JOSEPH D. DENBURGER, a citizen of the United States, residing at Lents, in the county of Multnomah and 5 State of Oregon, have invented certain new and useful Improvements in Machines for Calking Seams, of which the following is a specification.

This invention relates to calking machines for calking the seams of ships and the like.

The main object of the invention is to provide a simply constructed and efficient machine of this character which while compact and easily handled is yet quite as effective if not more so than those of more cumbersome construction.

Another object is to so construct a machine of this character that it may be used 20 for calking seams on both the deck and the outside of the hull of a ship and which may be also used for calking seams on any other structure.

With the foregoing and other objects in view, which will appear as the description proceeds, the invention resides in the combination and arrangement of parts and in the details of construction hereinafter described and claimed, it being understood that 30 changes in the precise embodiment of the invention herein disclosed may be made within the scope of what is claimed without departing from the spirit of the invention.

In the accompanying drawings:—

35 Figure 1 represents a front elevation of a machine constructed in accordance with this invention,

Fig. 2 represents a longitudinal vertical section taken on the line 2—2 of Fig. 1,

40 Fig. 3 is a top plan view thereof on a small scale, and

Fig. 4 is a horizontal section taken on the line 4—4 of Fig. 1.

In the embodiment illustrated, a casing 1 is shown having a tubular upright 2 depending therefrom and on which it is supported. A pair of oppositely disposed arms 3 and 4 are carried by the lower end of the tubular upright 2 and are here shown arcuate in 50 form although obviously they may be of other desired configuration. These arms are bifurcated at their lower ends and between the furcations 5 thereof are mounted wheels 6 which have knife edges 7 which adapt 55 them to travel in the seam to be calked.

The lower end of the tubular upright 2

has a chamber 8 which is designed to receive and house the calking blade or hammer 9. This blade 9 may be of any suitable or desired width and tapers toward its 60 lower edge as is shown clearly in Fig. 1. This blade 9 is carried by the lower end of a rod 10 which is mounted to reciprocate in the bore of the standard 2 and has a pitman 11 pivotally connected with its upper end, 65 the other end of said pitman being connected with a wrist pin 12 fixed to a crank disk 13 which is rotatably mounted in a partition 14 formed within the casing 1 and which divides the disk chamber 15 from another chamber 16 in which is rotatably mounted a shaft 17. A bevel cog 18 is fixed to the shaft 17 to rotate therewith and meshes with a larger bevel gear 19 which is fixed to one end of the shaft 20 which carries disk 13. It will thus be seen that when the shaft 17 is rotated motion will be imparted therefrom through the bevel gears 18 and 19 to the disk 13 and that the turning of this disk will operate through pitman 70 11 to reciprocate the rod 10 which carries the calking hammer 9.

The shaft 17 extends through the top of the casing 1 and has its terminal made angular as shown at 21 to receive the actuating 85 means for the shaft which may be a crank handle when the device is to be operated manually or a pulley when it is to be mechanically operated.

Mounted to rotate on an arm 22 which 90 projects laterally from upright 2, is a reel 23. Two arms 22 are provided to support this reel as is shown clearly in Fig. 3, said arms diverging for a certain distance and then extended parallel as shown at 22' having their terminals notched to form bearings 24 in which the trunnions 25 of the reel are designed to be rotatably mounted. This reel 23 is designed to have wound thereon the calking material which is in the form of 95 100 a cotton thread 26 of any suitable size necessary for filling the seams to be calked.

Extending laterally from one side of the tubular standard 2 near its lower end is a housing 27 in which is mounted the thread 105 feeding mechanism. This mechanism comprises a lever 28 which is fulcrumed at 29 on a projection 30 carried within the housing 27. This lever has a longitudinally extending slot 31 at one end and this slotted 110 end extends through a longitudinal slot 32 in the rod 10 as is shown clearly in Fig. 2,

a pin 33 extending through the side walls of the slotted portion of rod 10 and through the slot 31 in the lever 28 as is shown clearly in Fig. 1. A feeding finger 34 is pivotally connected with the outer end of lever 28 and tapers toward its free end, said end having an inturned spur 35 for engaging the thread 26 and forcing it forwardly under the hammer 9 when the finger 34 is moved forwardly and which releases from the thread when the finger moves rearwardly thereby preventing it from drawing back the thread 26 on its rearward movement.

15 The outer side wall of the housing 27 inclines downwardly and inwardly toward the lower end of the blade incasing chamber 8 and opens opposite the lower end of said chamber so that the thread 26 which is fed into the housing through a mouth 36 at its upper end will be passed under the hammer 9 during the operation of the machine as is shown clearly in Fig. 1.

20 A spring 37 is carried by the outer face of the standard 2 within the housing 27 and is here shown in the form of a plate spring fixed at one end to said standard with its free end bearing against the finger 34 and yieldably holding said finger in engagement with the thread 26, a guide being thus formed between the finger and the inclined wall of the housing as is shown clearly in Fig. 1.

25 It will thus be seen that when the rod 10 is reciprocated for lifting and lowering the hammer 9 the lever 28 will be correspondingly rocked and thereby impart a reciprocatory movement to the feed finger 34 so that when the rod 10 moves up the inner end of lever 28 will be carried with it and its finger carrying end will be moved downwardly thereby forcing the thread 26 into the path of hammer 9 and when the rod moves downwardly the hammer will be lowered thereby engaging the thread and driving it into the seam to be calked and simultaneously with the lowering of the hammer the feed finger will be raised ready for the next feeding action. It will thus be seen that these two elements, the blade 9 and the finger 34 reciprocate alternately so that one will supply the material to be calked by the other.

30 It will of course be understood that the wheels 6 operate as guides for the machine, being inserted in the seam to be calked, the material being fed into the seams by the mechanism above described between the wheels, and driven thereinto by the hammer 9 so that one of the wheels will travel in the uncalked portion of the seam and the other in the calked portion thereof.

35 By constructing this machine in the manner above described, it will be seen that a strong, compact, simple mechanism is pro-

vided which may be easily lifted by the operator and carried from place to place and readily held in operative engagement with the structure to be calked. It is so small that it may be used in places which are ordinarily inaccessible to machines of this character and thus will be equally effective for use on the inside or outside of a vessel.

40 From the foregoing description, taken in connection with the accompanying drawings, the advantages of the construction and of the method of operation will be readily apparent to those skilled in the art to which the invention appertains and while I have described the principle of operation of the invention together with the device which I now consider to be the best embodiment thereof, I desire to have it understood that the device shown is merely illustrative and that such changes may be made as are within the scope of the claimed invention.

45 I claim:—

1. In a calking machine, a supporting structure, guiding means therefor, a calking hammer, and a feeding device mounted for alternate reciprocation whereby the calking material is fed under the hammer ready for the driving blow thereof.

50 2. In a machine of the class described, a supporting structure, a calking hammer mounted to reciprocate thereon, a feeding device for supplying the calking material into the path of the hammer, and a connection between said hammer and said feeding device whereby the feeding device is reciprocated alternately relative to the hammer.

55 3. In a machine of the class described, a casing having a tubular standard depending therefrom, a rod mounted to reciprocate in said standard and having a calking hammer at its lower end, means mounted in said casing for reciprocating said rod, a lever fulcrumed intermediately of its ends on said standard and having one end engaged with said rod, and a finger carried by the other end of said lever and positioned to feed the calking material into the path of the hammer.

60 4. In a machine of the class described, a calking hammer mounted for reciprocatory movement, a feed finger for supplying the calking material into the path of the hammer, a spring for pressing said finger into yielding engagement with the material to be fed, and a connection between said finger and said hammer whereby they are alternately reciprocated on the actuation of the hammer.

65 5. In a machine of the class described, a rod mounted to reciprocate, a calking hammer carried by one end of said rod, actuating means connected with the other end thereof, a lever of the first class having one end pivotally connected with said rod, a

feeding finger pivotally connected with the other end thereof, said finger tapering toward its free end and having a material engaging spur at its free end, a spring normally forcing said finger into the path of the material to be fed, a support positioned opposite said finger and forming a guideway between it and the finger for the calking material, said guide opening adjacent the path 5 of said hammer whereby when the hammer is raised the material will be fed thereunder ready to receive its driving blow.

6. In a machine of the class described, a casing having a tubular standard depending therefrom and communicating therewith, a disk rotatably mounted in said casing, a rod mounted to reciprocate in said standard, a link connecting the upper end of said rod eccentrically with said disk, means connected to rotate said disk, the lower end of said standard having a chamber therein registering with the bore of the standard, a blade carried by said rod and normally housed within said chamber, said rod having 10 a slot extending longitudinally thereof, a laterally extending housing carried by said standard, a lever fulcrumed intermediately of its ends within said housing and having one end slotted and extending through 15 the slot within said rod, a pin extending

through the side walls of the slot in the rod and through the slot in said lever, a feed finger carried by the other end of said lever, the outer wall of said housing being inclined downwardly and inwardly, said housing 20 having an opening arranged adjacent the path of the hammer, and a mouth at its other end through which the calking thread is designed to pass, and spring means for normally forcing the feeding finger into yieldable engagement with the calking thread which is guided between said finger and the inclined wall of said housing.

7. In a machine of the class described, a supporting structure, a rod mounted to reciprocate therein, a calking hammer carried by one end thereof, actuating means connected with the other end thereof, a feed finger for supplying the calking material into the path of said hammer, a connection 25 between said finger and rod whereby said rod and finger are reciprocated alternately, and means carried by said structure for supplying the calking material to said finger.

In testimony whereof I affix my signature 30 in presence of two witnesses.

JOSEPH D. DENBURGER.
